(57) **CLAIM**

The ornamental design for a foldable bench, as shown and described.

DESCRIPTION

FIG. 1 is a perspective view of the foldable bench in an unfolded configuration;

FIG. 2 is a close-up perspective view detailing a left end portion of the foldable bench in FIG. 1;

FIG. 3 is a front elevation view of the foldable bench in an unfolded configuration;

FIG. 4 is a rear elevation view of the foldable bench in an unfolded configuration;

FIG. 5 is a close-up front elevation view detailing a left end portion of the foldable bench in FIG. 3;

FIG. 6 is a close-up front elevation view detailing a right end portion of the foldable bench in FIG. 3;

FIG. 7 is a close-up front elevation view detailing a left end portion of the foldable bench in FIG. 4;

FIG. 8 is a close-up front elevation view detailing a right end portion of the foldable bench in FIG. 4;

FIG. 9 is a left side elevation view of the foldable bench in an unfolded configuration;

FIG. 10 is a right side elevation view of the foldable bench in an unfolded configuration;

FIG. 11 is a close-up left side elevation view detailing a portion of the foldable bench in FIG. 9;

FIG. 12 is a close-up right side elevation view detailing a portion of the foldable bench in FIG. 10;

FIG. 13 is a top plan view of the foldable bench in an unfolded configuration;

FIG. 14 is a bottom plan view of the foldable bench in an unfolded configuration;

FIG. 15 is a close-up top plan view detailing a left end portion of the foldable bench in FIG. 13;

FIG. 16 is a close-up top plan view detailing a right end portion of the foldable bench in FIG. 13;

FIG. 17 is a close-up bottom plan view detailing a left end portion of the foldable bench in FIG. 14;

FIG. 18 is a close-up bottom plan view detailing a right end portion of the foldable bench in FIG. 14;

FIG. 19 is a perspective view of the foldable bench in a folded configuration;

FIG. 20 is a close-up perspective view detailing a left end portion of the foldable bench in FIG. 19;

FIG. 21 is a close-up perspective view detailing a right end portion of the foldable bench in FIG. 19;

(Continued)

FIG. 22 is a front elevation view of the foldable bench in a folded configuration;
FIG. 23 is a right side elevation view of the foldable bench in a folded configuration;
FIG. 24 is a close-up front elevation view detailing a left end portion of the foldable bench in FIG. 22;
FIG. 25 is a close-up front elevation view detailing a right end portion of the foldable bench in FIG. 22; and,
FIG. 26 is a close-up right side elevation view detailing a portion of the foldable bench in FIG. 23.
The broken lines for illustrative purposes only and form no part of the claimed invention.
